UNITED STATES PATENT OFFICE.

CHARLES PEARSON, OF CHICAGO, ILLINOIS, ASSIGNOR TO INTERNATIONAL HARVESTER COMPANY, A CORPORATION OF NEW JERSEY.

LATCHING MECHANISM.

1,424,936.

Specification of Letters Patent. Patented Aug. 8, 1922.

Application filed September 18, 1919. Serial No. 324,475.

To all whom it may concern:

Be it known that I, CHARLES PEARSON, a citizen of the United States, residing at Chicago, in the county of Cook and State of Illinois, have invented certain new and useful Improvements in Latching Mechanism, of which the following is a full, clear, and exact specification.

This invention relates to latching mechanism which is adapted for latching any two desired elements together, but has been worked out in this instance for the purpose of latching one frame member to another frame member.

15 The object of the invention is to provide means whereby two elements may be automatically latched together when one of the elements is properly positioned with respect to the other.

20 A further object is to provide means whereby two elements may be securely locked together in engagement with each other; and a still further object is to provide latching mechanism which may be locked in 25 either open or closed position.

The latching mechanism by means of which the above objects are carried out comprises a latching member which is in this instance pivoted intermediate its length, and 30 a latch controlling member which is movable with respect to the latch, and is adapted in its different positions of adjustment to hold the latch in open position, to hold the latch in closed position and to permit 35 free movement of the latch about its pivot.

One embodiment of the invention has been illustrated in the accompanying drawings, and in these drawings—

Fig. 1 is a top plan view, partly in section, showing my improved latching mechanism in closed position;

Fig. 2 is a top plan view similar to Fig. 1, but showing the latch held in open position;

Fig. 3 is a side elevation of the construction shown in Fig. 1;

Fig. 4 is a vertical sectional view taken substantially on the line 4—4 of Fig. 3, looking in the direction of the arrows; and

Fig. 5 is an elevational view showing a 50 portion of the frame member to which the latching member is secured.

In the embodiment of the invention shown, the latch is carried by a frame mem-

ber 10 which is preferably formed of channel iron as shown in Fig. 4, this member 55 having flanges 11 and 12. The latching mechanism is secured between the flanges 11 and 12, being carried by a casting 13 which is securely bolted to the vertical web of the channel member 10, as shown at 14. The 60 casting 13 is provided with lateral flange portions 15 adjacent its rear ends, these flange portions having aligned transverse apertures 16. The latch is pivotally mounted on a pair of oppositely disposed pivot 65 members 17 which are inserted into the apertures 16 against the pressure of two oppositely disposed springs 16', the purposes of which are hereinafter described. The latch pivot portion or barrel 18 is mounted for 70 free oscillation on the pivot pin 17. The latch extends on both sides of the barrel portion 18, forming a lever, one end portion 19 having formed on its end an offset latching portion 20 and the opposite end of 75 the lever or latch having a recess or pocket 21 formed therein for the reception of a spring 22 which is interposed between the base of the pocket and the portion of the wall of the channel member 10, as clearly 80 illustrated in Figs. 1 and 2.

Means has been provided for controlling the position of the latching lever in such a manner that the latch may be locked in open or closed position, or may oscillate freely 85 about its central pivot. This controlling means comprises a crank member 23 which is screw-threaded on one end, as shown at 24, this screw-threaded portion 24 passing through an elongated aperture 25 formed 90 in a vertical web of the channel member 10 and being received by screw-threaded aperture 26 formed in the barrel portion 18 of the latch. This crank member 23 is held in the different positions of adjustment by the 95 two oppositely disposed springs 16' which engage the threaded portion 24 of the crank member. As clearly illustrated in Fig. 4, the screw-threaded aperture 26 is formed obliquely in the latch and is also inclined 100 with respect to the plane indicated by the line 4—4 when the latch is disposed in its open or closed position as shown in Figs. 1 and 2. The latching portion 20 of the latching lever is adapted to engage an off-set lug 27 which is formed on the free end 105

of a supporting member or frame member 28 which is adapted to be connected by the latch with the channel member 10. The various positions of adjustment of the latch are shown in Figs. 1 to 3, inclusive, Fig. 1 showing the latch controlling member 23 in the position assumed when the latch is positively locked in latching position. The inclination of the aperture 26 5 formed in the barrel portion 18 of the latching lever causes the portion 19 of the lever to be swung inwardly toward the vertical web of the frame member 10 when the crank is thrown to the left, as shown in Fig. 1. When the crank is swung to an intermediate position, as shown in dotted lines in Fig. 2, it will be disposed in a position out of engagement with the vertical web 10 and the latch freely swings on its 10 pivot pins 17, the spring 22 tending to force the latching portion 19 of the latch toward the vertical web of the member 10. When the controlling member is in this intermediate position, the supporting member 28 15 may be forced rearwardly into latching position, and when it comes into this position the latch will be swung outwardly against the tension of the spring 22 until the lug 27 has been moved to its rear position, whereupon the latch will be forced 20 inwardly again by the spring to the position shown in dotted lines in Fig. 2. When the controlling member 23 is swung to the extreme right, as shown in Fig. 2 in full lines, 25 the latch will be positively moved to its open position, being forced outwardly against the tension of the spring 22. When the latch is in this position, the support or frame member 28 may be moved to a latching 30 position and when it has reached that position the controlling lever may be again swung to the left, thereby positively locking the member 10 and the member 28 together.

From the above description of the construction and operation of my improved latching mechanism, it will be seen that I have provided a latch which may be positively held in either open or closed position, or which may be so adjusted that it may be 45 oscillated freely about its pivot. This form of latch has been found especially satisfactory for coupling implement frame members to tractor frame members, but it will of course be obvious that the device is not 50 limited in any way to this particular use, but may be utilized wherever a latch is desired for the purpose of connecting the two members together.

While I have in the above specification 55 described one specific embodiment of my invention, it will be evident that the invention is capable of modification, and that modifications and changes may be made without departing from the spirit and scope

of the invention defined in the following 60 claims:

1. A latching mechanism comprising in combination a pivoted latching member, resilient means for forcing said latching member in one direction about its pivot and controlling means having an oblique pivotal connection with said member for locking the member in open position against the tension of said resilient means. 70

2. A latching mechanism comprising in combination a pivoted latching member and controlling means for said latching member pivoted to said latching member on an axis inclined to a plane perpendicular to the pivotal axis of said latching member. 75

3. A latching mechanism comprising in combination a pivoted latching member having a screw-threaded aperture therein inclined with respect to the pivotal axis of said member, and controlling means for said latching member having screw-threaded engagement with the screw-threaded aperture in said member. 80

4. A latching mechanism comprising in combination a pivoted latching member and a crank member inclined thereto and having screw-threaded engagement therewith for controlling the position of said latching member. 90

5. In a latching mechanism, the combination of a frame member, a latch pivoted thereto, a crank engaging the frame member and pivoted to the latch on an axis oblique to and intersecting the pivotal axis thereof, whereby the latch will be held close in one position of the crank, open in another position of the crank, and be free to oscillate on its pivot in an intermediate position of the crank. 95

6. In a latching mechanism, the combination of a frame member, a latch pivoted thereto, an actuating lever pivoted to the latch on an oblique axis and adapted when in one position of adjustment to hold the latch closed, in another position to hold the latch open, and in a third position to permit the latch to oscillate on its pivot. 100

7. A latching mechanism comprising in combination a pivoted latching member, a crank member having a screw-threaded connection therewith, the axis of rotation of said crank member being so inclined with respect to the pivotal axis of said latching member that said crank member when in one position of adjustment will lock said latching member in closed position, when in another position of adjustment will lock said member in open position and when in a third position of adjustment will permit free oscillation of said latch on its pivot. 115

In testimony whereof I affix my signature.

CHARLES PEARSON.
